(57) CLAIM

The ornamental design for a microfluidic cartridge, as shown and described.

DESCRIPTION

FIG. 1 is a front perspective view of a microfluidic cartridge of the new design;

FIG. 2 is a top plan view thereof;

FIG. 3 is a front elevation view thereof;

FIG. 4 is a rear elevation view thereof;

FIG. 5 is first side view thereof; and,

FIG. 6 is a second side view thereof.

The broken lines in FIGS. 1 through 6 are for illustrative purposes only and form no part of the claimed design.
